UNITED STATES PATENT OFFICE.

FREDERICK THORNTON, OF HUNTINGTON, WEST VIRGINIA.

TROLLEY-WHEEL.

1,278,398.

Specification of Letters Patent. Patented Sept. 10, 1918.

Application filed July 16, 1917. Serial No. 180,781.

To all whom it may concern:

Be it known that I, FREDERICK THORNTON, a citizen of the United States, residing at Huntington, in the county of Cabell 5 and State of West Virginia, have invented certain new and useful Improvements in Trolley-Wheels, of which the following is a specification.

This invention relates to trolley harps 10 and wheels, and particularly to that class having means for supplying lubricant to the wheel journals.

The objects of the invention are to provide an improved device of exceptionally 15 simple construction, in which the parts are easily removable for renewal or repair, and in which novel and efficient means are provided for feeding lubricant to the bearings. The invention also contemplates the provision of a novel form of bearing in which 20 loosening of the wheel, due to wear, is practically eliminated.

In order that the invention may be readily understood, reference is had to the accompanying drawings, forming part of this 25 specification, and in which:

Figure 1 is a side elevation of the complete harp and trolley as it appears when mounted on a pole ready for use;

Fig. 2 is a central, longitudinal section with the wheel removed, parts being in elevation;

Fig. 3 is a transverse section on the line 3—3 of Fig. 1, looking in the direction of the arrow;

Fig. 4 is a perspective view of the trolley harp itself;

Fig. 5 is a perspective view of one of the bearing brackets;

Fig. 6 is a top plan view of one of such brackets; and,

Fig. 7 is a perspective view of one of the removable bearing bosses.

Referring to the drawings in detail, 1 45 designates the trolley harp in its entirety, which is provided with a socket adapted to receive the end of the usual trolley pole 2. The preferred method of connecting the harp to the pole is by means of a cross pin 3, passing through the end of the pole. The harp is provided with a pair of longitudinal grooves 4, adjacent the socket, through which grooves the ends of the pin 3 pass when the pole is being inserted. The

harp is further provided with a pair of 55 notches 5, spaced 90 degrees from the grooves 4, in which notches the ends of the pin 3 seat when the parts are in assembled relation, as shown in Fig. 3. The side walls of the harp are cut away, as shown at 6, to 60 afford ventilation and to prevent the burning of the harp to the pole. A perforated lug or eye 7 is formed in the harp for the reception of the retriever rope, as usual.

The harp is formed with a pair of spaced 65 arms 8 and 9, preferably having strengthening ribs 10 on their outer sides, and formed at their ends with rectangular notches 11 and 12, respectively. Near their base, the arms are formed with bosses 13 70 through which pass alined openings 14—15, adapted to receive a bolt, as hereinafter described. On their inner faces, above the bolt holes 14 and 15, the arms are provided with spring receiving pockets 16—17, as 75 clearly shown in the drawing.

Supported by the arms 8 and 9 of the harp is a pair of bearing brackets or members 18 and 19. These members are duplicates of each other except that they are 80 reversely formed, and a description of one will suffice for both. One of the members is shown in Fig. 5 and comprises a shank having at its lower end a bolt receiving eye 21, and a disk-shaped body portion 22. On 85 the inner face of the body portion 22 is formed a curved annular rib 23, for a purpose hereinafter described. The disk-shaped body 22 is formed hollow to provide a lubricant chamber 24, having 90 an opening 25 in its upper edge through which the chamber may be filled. Adjacent the opening 25 is an upstanding lug 28, having an inclined outer surface arranged as shown. The lower part of the 95 disk-shaped member 22 is cut away as indicated at 27, for the purpose of reducing the weight of the bearing member. It will be understood, of course, that the chamber 24 is not open at this point, but is closed 100 by means of a flat bottom.

At the center of the member 22 is an inwardly projecting boss 29, having a rectangular opening 30 extending therethrough. This opening is adapted to receive the similarly shaped shank 31 of a removable bearing boss 32, shown in perspective in Fig. 7. This bearing boss is

preferably conoidal in shape, approaching the form of a paraboloid, except that the extreme point is cut away to form a flattened end, as clearly shown at 33. A plurality 5 of longitudinally extending grooves 34 are formed in the surface of the conoidal member for the purpose of distributing the lubricant over the surface thereof.

Referring to Fig. 3, it will be seen that 10 the base of the conoidal member 32 is disposed concentric with the rib 23, but separated from the inner edge of such rib by a space 26, which space forms a passage for the lubricant from the chamber 24 into the 15 grooves 34. The ends of these grooves adjacent the chamber 24 are open so as to readily receive the lubricant.

In practice, a pair of bearing brackets such as described is mounted between the 20 arms 8 and 9, with the shanks 31 projecting through the brackets and seated in the notches 11-12 in the arms. The trolley wheel 35 is mounted between these brackets and is provided at each side with an annular groove 36, into which the ribs 23 snugly fit, so as to exclude dust from the bearings and prevent the escape of the lubricant. The wheel 35 is further provided 25 with central, axial sockets adapted to receive the bearing bosses 32. These sockets are lined with bushings 37, formed of wear-resisting material, such as hardened steel. The bosses 32 are also formed of very hard polished steel. Lubricant in the form of a 30 stiff grease is packed into the chamber 24 from which it works its way along the grooves 34 into the bearing sockets, and I have found in practice that a journal having wearing surfaces comprising steel on 35 steel, lubricated as described, produces a bearing of exceptionally long life.

The bearing brackets are retained in position by means of a single bolt 38, passing through the eyes 21 in the brackets and the 40 holes 14-15 in the arms of the harp. In order to compensate for such slight wear of the bearings as does occur, I place leaf 45 springs 39, of semi-elliptical form, in the pockets 16-17, so that they bear upon the outside of the brackets and urge them inwardly toward the wheel.

It will be particularly understood that 50 while the sockets in the wheel 35 are complete conoids, having their surfaces formed by the revolution of a smooth curve about the axis, the ends of the conoidal bosses 32 are cut away or flattened, as shown, so as to provide a space between the end of the boss and the bottom of the socket. In other 55 words, the point of the bearing boss does not contact with the center of the socket. By virtue of this construction, it is possible for the springs 39 to force the bosses farther into the sockets to compensate for 60 wear, and thus maintain the outer portions 65

of the bosses in contact with the corresponding portions of the sockets, so as to prevent wabbling of the wheel. It will be understood, of course, that the shanks 31 seat loosely in the notches 11 and 12, and that 70 the bearing brackets are capable of sliding freely upon the bolt 38.

It will be seen that if it is necessary to renew the bearing bosses, they may be readily removed from the brackets by tapping 75 on the outer ends of the shanks 31, and that the brackets themselves may be quickly removed from the harp by simply releasing the single bolt 38.

The function of the lugs 28 is to act as 80 guards or guides to prevent the trolley wire catching or hanging on the bearing brackets. Should the wire become displaced from the groove of the wheel it will ride down the outer beveled face of one of these lugs 85 and thus be caused to clear the bracket.

What I claim is:

1. In a device of the character described, a trolley harp having a pair of spaced arms, said arms having notches in their ends, a 90 pair of bearing brackets supported by said arms and having lugs engaging said notches, a trolley wheel mounted between said brackets, and a single bolt passing through said arms and brackets below the wheel and securing the parts in position.

2. In a device of the character described, a trolley harp having a pair of spaced arms, said arms having notches in their ends, a 100 pair of bearing brackets supported by said arms and having lugs engaging said notches, a trolley wheel mounted between said brackets, a single bolt passing through said arms and brackets below the wheel, and securing the parts in position, the brackets being 105 slideable on said bolt, and springs interposed between said arms and brackets tending to urge the latter together toward said wheel.

3. In a device of the character described, a trolley harp having a pair of spaced arms, 110 said arms having notches in their ends, a pair of bearing brackets supported by said arms, removable bosses having shanks extending through said brackets and forming lugs engaging said notches, a trolley wheel 115 mounted between said brackets and having journal sockets into which said bosses fit, and means for securing said parts together.

4. The combination with a trolley harp, 120 of a pair of bearing brackets carried thereby, each bracket having a central bearing boss and a surrounding annular rib spaced from said boss, and a trolley wheel mounted between said brackets, said wheel having central sockets to receive said bosses, and 125 annular grooves to receive said ribs.

5. The combination with a trolley harp, 130 of a pair of bearing brackets carried thereby, a central bearing boss projecting from each bracket and constituting a journal,

each bracket being formed hollow to provide a lubricant chamber, and having an annular space surrounding the boss and communicating with said chamber, and a wheel mounted between said brackets and having axial sockets engaging said bosses.

6. The combination with a trolley harp, of a pair of bearing brackets carried thereby, a central bearing boss projecting from each bracket and constituting a journal, each bracket being formed hollow to provide a lubricant chamber, and having an annular space surrounding the boss and communicating with said chamber, and a wheel mounted between said brackets and having axial sockets engaging said bosses, each boss having grooves in its surface, whereby lubricant is fed from said chamber through said annular space and along said grooves, and thus distributed over the journals.

7. The combination with a trolley harp of a pair of disk shaped bearing brackets carried thereby, a central boss mounted on each bracket, the disk shaped brackets being formed hollow to provide annular lubricant chambers, each bracket having a space adjacent the boss through which lubricant can pass from said chamber, and a trolley wheel

mounted between said brackets and having journal sockets into which said bosses fit. 30

8. The combination with a trolley harp, of a pair of disk shaped bearing brackets carried thereby, a central boss mounted on each bracket, the disk shaped brackets being formed hollow to provide annular lubricant 35 chambers, each bracket having a space adjacent the boss through which lubricant can pass from said chamber and an opening in the edge of the disk through which said chamber may be filled, and a trolley wheel 40 mounted between said brackets and journaled on said bosses.

9. The combination with a trolley harp, of a pair of disk-like bearing brackets carried thereby, a trolley wheel of larger diameter 45 than the disks mounted between said brackets, and a lug carried by the upper edge of each bracket and projecting substantially to the periphery of said wheel, said lug having a beveled outer face extending from the 50 edge of the wheel to the outer face of the bracket.

In testimony whereof I have affixed my signature.

FREDERICK THORNTON.
